UNITED STATES PATENT OFFICE.

EDWARD J. DE VILLE, OF DAYTON, OHIO, ASSIGNOR TO THE MONARCH ENGINEERING COMPANY, OF DAYTON, OHIO, A CORPORATION OF OHIO.

AUTOMATIC SWITCH.

Application filed April 7, 1921. Serial No. 459,268.

This invention relates to electric switches and more particularly to those of the quick acting or snap over type.

The object of the invention is to simplify 5 the structure as well as the means and mode of operation of such devices, whereby they will not only be cheapened in construction, but will be more efficient in use, positive in 10 operation, uniform in action, durable, and unlikely to get out of repair.

A further primary object of the invention is to provide an improved form of 15 contact fingers, or yielding switch blade, so shaped and arranged that it will effect a slight shifting or wiping movement, subsequent to its engagement with the terminal or contact to insure a clean surface engagement between the parts.

A further object of the invention is to 20 provide in addition to the usual quick acting tumbling mechanism by which the switch is actuated, a positive knock-out to mechanically and positively effect a disengagement of the contact terminal in the 25 event that the tumbling mechanism fails to operate or having operated, fails to effect such disengagement.

A further object of the invention is to so 30 construct and arrange the various elements of the tumbling mechanism, whereby they will be adapted for standardized production, with maximum economy of manufacture, and whereby unskilled persons may 35 disassemble and assemble the parts, for inspection, repairs, and replacements, without the necessity of hand tools.

With the above primary and other incidental objects in view as will more fully appear in the specification, the invention 40 consists of the features of construction, the parts and combinations thereof, and the mode of operation, or their equivalents as hereinafter described and set forth in the 45 claims.

Referring to the drawings, Fig. 1 is a side 50 elevation partly in section of the assembled switch mechanism embodying the present invention. Fig. 2 is a side elevation from the left of Fig. 1, with the switch contact and insulating supporting plate removed.

Fig. 3 is a side elevation similar to Fig. 1, showing the tumbling mechanism and switch in its operated position. Fig. 4 is a perspective view of the switch blades and 55 supporting plate removed from Fig. 2.

Like parts are indicated by similar characters of reference thruout the several views.

Automatic quick acting switches of the general type herein shown and described are extensively used in conjunction with electrically operated pneumatic pressure pumping and water distribution systems, and other analogous installations for automatically connecting and disconnecting the actuating motor at predetermined minimum and 60 maximum degrees of pressure, and in association with gravity distribution fluid systems, wherein the switch is controlled by the rise and fall of a float within a tank. Switches of this character likewise find 70 many applications thruout a wide range of usefulness.

In the pressure type of automatic switch herein shown and described for illustrative purposes, there is employed a main upright 75 side frame or plate 1, attached to a base having therein a pressure chamber 2, one side of which is formed by a flexible diaphragm 3. The underside of the flexible diaphragm 3 is subjected to variations of 80 fluid pressure, whereby the diaphragm is flexed upwardly against the tension of a helical spring 4, which exerts its pressure in opposition to that of the fluid within the chamber 2. The spring 4 abuts at its lower 85 end upon a presser head 6, carried by the diaphragm 3, and at its upper end against an adjustable thimble or sleeve 7, screw threaded in a lug 8 projecting from the side frame 1. The abutment sleeve 7 is screw 90 threaded within the lug 8, whereby the rotation of the sleeve 7 will tend to increase or relieve the tension of the spring 4, causing it to resist to greater or less extent the 95 pressure within the chamber 2. It will be understood that as the pressure increases within the chamber 2, the diaphragm 3 rises against the tension of the spring 4, and as the pressure decreases the spring 4 by its 100 expansion, depresses the diaphragm in proportion to the decrease of fluid pressure. Attached to the presser head 6 and extending axially thru the helical spring 4, and abutment sleeve 7, is a reciprocating rod or 105 stem 9, connected at its upper end to an oscillating arm 10, pivoted at 11 to the side frame 1. The extremity of the arm 10 is slotted or bifurcated for ready engagement with a transverse pin 12 extending between the laterally disposed arms of a bifurcated 110

bell crank lever 13, pivoted at 14 upon a stud projecting from the side plate 1. The lower or downwardly extending arms of the bifurcated bell crank lever 12, carrying 5 loosely journalled therein a transverse pin 14. The medial portion of the pin is flattened, as at 15, and perforated to permit the free reciprocation therethru of a stem 16, projecting medially from a U-shaped 10 yoke 17, the trunnions 18 of which have pivotal connection in the slotted end of an oscillatory switch operating lever 19. This switch lever 19 is pivoted on a stud 20 projecting from the side plate 1. The bell crank 15 lever 13 and switch lever 19 are capable of independent oscillatory movement in relation one with the other, to and fro across a dead center. Surrounding the stem 16 of the yoke 17 and bearing at one end 20 upon a flattened central portion 15 of the pin 14 carried by the bell crank lever, and at its opposite end upon the inner portion of the bight of the swinging yoke 17 is a helical spring 21, which is placed under 25 tension as the levers 12 and 19 approach a dead center position. The reaction of the compressed spring 21, as the levers pass the dead center position, actuates the switch lever 19 suddenly and fully to an opposite 30 or reverse position. The switch lever 19 is operatively connected by a link 22, with a transverse bar 23, carried by the contact arms 24 of the switch. Thus as the arm 19 is oscillated to and fro, it carries with it 35 the switch arms 24 causing them to make and break contact with electric terminals 25 carried upon a plate 26 of insulation.

Upon an increase of pressure within the chamber 2, (Fig. 1) the stem 9 is forced 40 upwardly and with it the arm 10, which movement is transmitted to the bell crank lever 12, oscillating the downwardly extending arm thereof forwardly or toward the left in Fig. 1. This movement it will be 45 understood is quite gradual and may occupy a considerable period of time before the fluid pressure sufficiently overcomes the tension of the spring 4, to enable the movement of the pin 14 to a dead center relation with the centers 13 and 18 of the bell crank lever 12 50 and yoke 17 respectively. This movement of the pin 14 to the dead center position will serve to tension the spring 21, and as the pin 14 passes the dead center, this spring 55 by its expansion suddenly forces the switch lever 19 thru a full stroke toward the right, whereupon the parts resume the positions shown in Fig. 3. This movement of a lever 19 withdraws the contact arm 24 from 60 engagement with the terminal 25 and opens the electric circuit. As the fluid pressure within the chamber 2 decreases, the spring 4 exerts a downward pressure to effect a reverse movement of the parts against compressing the spring 21 until a dead center 65

position is reached, whereupon the spring by its expansion will return the several parts to the positions shown in Fig. 1.

The switch arms 24 are attached to the outer side of the insulation supporting plate 26 and pass about the top edge thereof by being formed into a bight 28 of substantially three fourths of a circle, and extending thence downwardly to a point opposite the terminals 25. The circular bight 28 not only affords flexibility for oscillatory vibration of the arms 24 to and from the terminal 25, under the influence of the switch arm 19, but also permits sufficient flexibility to permit a somewhat longitudinal reciprocation of the contact arms 24 in addition to their oscillatory movement. The contact arms 24 are so proportioned and the connecting link between the contact members and the switch arm 19 is of such length that the arms 24 will engage the terminal 25 before the switch arm 19 has completed its movement. The further flexing of the arms 24 subsequent to their engagement with the terminals 25 effects a sliding or wiping movement of the arms 24 over the terminals 25 due to the flexibility of the circular bight 28 which yields under the continuous pressure of the switch arm 19. This wiping movement as the circular bight 28 yields 90 serves to clean the contact surfaces and preserve them bright and in condition for perfect electrical conductivity.

As a safety precaution to insure the disengagement of the contact member upon reversal of the automatic tumbling mechanism, there is provided a mechanical "knock-out" 100 for positively disengaging the terminals in the event that they should remain in contact. Such a possibility is rather remote, yet the tumbler mechanism might become stiff or unyielding thru the accumulation of dirt or oil or some foreign body might accidentally come into the path of movement of some of the parts, thereby arresting their 105 operation. To avoid any such condition, there is provided a bell crank lever 30, pivoted at 31 to a lug projecting from the base of the main frame, one arm of which extends thru a slot 32, in the insulation plate 26, to a point in proximity to the tie bar, connecting the contact arms 24 to which the switch arm 19 is attached. The opposite arm of the bell crank lever 30 engages in the slotted end of a short lever 33, pivoted 110 on the stud 20 to which the switch arm 19 is independently connected. That is to say, the lever 33 and the switch arm 19 are concentrically pivoted upon the same stud 20, but each is capable of oscillatory movement 115 independent of the other. The opposite arm of the lever 33 projects into the path of the preser head 6 carried by the diaphragm 3. Sufficient clearance is permitted between the preser head and the lever 33 so that under 120

ordinary conditions the tumbler mechanism will be tensioned and will have passed the dead center before the head 6 operatively moves the lever 33. However, as the head 6 approaches the limits of its upward movement, it engages the lever 33 oscillating the same about its pivotal stud 20 and thru its interengagement with the lateral arm of the bell crank lever 30 it oscillates the upper 10 arm or knockout lever inwardly or toward the right in Fig. 1 against the tie bar of the contact arms 26. If the tie bar of the contact arm has not already been moved out of the path of the knock out lever 30 by 15 the reversal of the switch lever 19 under the influence of the tumbler mechanism, this knock out lever 30 will positively move the tie bar to disengage the contact arm 26 from the terminals 25 forcibly breaking 20 their engagement in the event that they have been burned or welded together and by pressure against the connecting link and switch lever 19, the tumbling mechanism is positively reversed if it has not already performed its function. Thus the disconnection 25 of the switch and motive power is absolutely insured upon the rise of the fluid pressure to an abnormal degree. It is made certain that the actuating motor will be disconnected 30 before the pressure reaches a dangerous stage.

It will be noted that the connection of the link 22 with the switch lever 19 at one end and with the bar 23 at the other end is such 35 that a direct pressure is afforded until the contact 25 is engaged by switch blades at which time the connection of the link with the bar 23 will be somewhat below its connection with the lever 19. This affords a diagonal or downward pressure upon the tie bar 23, during the further throw of the lever 19. It is this downward or diagonal pressure which insures the wiping action of the switch blades upon the contact terminal. 40 This movement is compensated for by the distortion of the bights 28.

From the above description it will be apparent that there is thus provided a device of the character described possessing the 45 particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, 50 it is to be understood that the invention is not limited to the specific details shown, but that the means and construction herein disclosed comprise but one of several modes of putting the invention into effect, and the invention is therefore claimed in any of its 55

forms or modifications within the legitimate and valid scope of the appended claims.

Having thus described my invention, I claim:

1. In a switch operating mechanism, the 70 combination with an electric switch of an actuator, a snap over switch operating mechanism tensioned by said actuator to effect the reversal of the switch, and a knock out device operated by the actuator mounted independent of the snap over mechanism and unaffected by the initial movement of the actuator, by which the operation of the snap-over mechanism is achieved, the operation of 75 said knock out device being initiated by the final movement of the actuator, subsequent to the setting of snap-over mechanism to positively disengage the switch upon failure of the snap over medium to function.

2. In a switch operating mechanism, a 85 movable switch member, an oscillatory lever into the path of movement of which the switch element projects, means for oscillating the lever to disengage the switch element, and spring actuated means mounted 90 independent of said lever for actuating the switch element in advance of the movement of the lever and independent thereof.

3. The combination with a movable switch element, of a quick acting snap over actuating mechanism for the switch element, and a positive acting actuator for the switch element, said snap over mechanism and positive acting actuator being mounted for independent operation under a common propelling influence. 95

4. In an electric switch, a flexible switch blade, a support therefor, a circular bight formed in the blade adjacent to its point of attachment to the support, a contact terminal with which the blade engages, and actuating means for moving the switch to and from the terminal, said means being adapted to impart movement to the blade 105 subsequent to its engagement with the terminal thereby distorting the bight and effecting a wiping action of the blade upon the terminal. 110

5. In an electric switch, a contact terminal, 115 a flexible switch blade co-acting therewith and offset adjacent to its point of attachment whereby the blade is capable of a limited yielding movement in the plane of the main portion of the blade in addition to its movement to and from the terminal, means for flexing the blade to and from its terminal, said blade and terminal being arranged for interengagement before the flexing means reaches the limit of its movement 120 whereby the blade is further flexed subsequent to its engagement with the terminal, the offset attaching portion of the blade yielding under such further flexing movement to permit a wiping movement of the 125 blade in contact with the terminal. 130

6. In an electric switch, a contact terminal, a flexible switch blade coacting therewith, a support therefor, and a bight formed in the flexible blade adjacent to its point of attachment, means for flexing the blade into engagement with the terminal and by further movement flexing the bight of the blade subsequent to the engagement with the terminal by which blade is given shifting movement upon the terminal.
7. In a switch operating mechanism, the combination with an electric switch of two sets of automatic actuating mechanism for said switch independently mounted for separation.

rate operation both controlled by the same 15 impelling influence and timed to operate one in advance of the other.

8. In a switch operating mechanism, the combination with an electric switch of quick acting snap over mechanism for automatically reversing said switch, and means separate from said snap-over mechanism for automatically actuating the switch in the event of the non-operation of said quick acting snap over mechanism.

In testimony whereof, I have hereunto set my hand 28th March A. D. 1921.

EDWARD J. DE VILLE.
